[57] **CLAIM**

The ornamental design for a flashlight, as shown and described.

DESCRIPTION

FIG. 1 is a perspective view of a flashlight showing our new design;

FIG. 2 is a front elevational view of the flashlight shown in FIG. 1;

FIG. 3 is a rear elevational view of the flashlight illustrated in FIG. 1;

FIG. 4 is a right-side elevational view of the flashlight shown in FIG. 1;

FIG. 5 is a left-side elevational view of the flashlight shown in FIG. 1;

FIG. 6 is a top plan view of the flashlight shown in FIG. 1;

FIG. 7 is a bottom plan view of the flashlight shown in FIG. 1;

FIG. 8 is a perspective view of an alternative configuration of the flashlight shown in FIG. 1;

FIG. 9 is a second perspective view of the alternative configuration shown in FIG. 8;

FIG. 10 is a perspective view of an alternative embodiment of a flashlight similar to the embodiment illustrated in FIG. 1, incorporating a mounting saddle;

FIG. 11 is a side-elevational view of the flashlight shown in FIG. 10; and,

FIG. 12 is an alternative embodiment of a flashlight similar to the embodiment illustrated in FIG. 10, having modified gripping surfaces.

Broken lines represent lines of tangency of curved surfaces for shading purposes.
